[57] CLAIM

The ornamental design for fireplace air inlet, as shown
and described.

DESCRIPTION

FIG. 1 is a top, front perspective view of a fireplace air
inlet, showing my new design and shown with the door
fully opened;

FIG. 2 is a top, front perspective view thereof, shown
with the door closed;

FIG. 3 is a rear perspective view of the fireplace air
inlet as it appears in FIG. 2.
